AIR MIXER

Filed Feb. 25, 1928

UNITED STATES PATENT OFFICE

WILLIAM C. BREWER, OF TOLEDO, OHIO

AIR MIXER

Application filed February 25, 1928. Serial No. 256,863.

This invention relates to combustion promotion.

This invention has utility as an air pre-warmer accessory for ready installation, 5 more particularly in stoves or furnaces.

Referring to the drawings:

Fig. 1 is a fragmentary front view of a furnace having an embodiment of the invention incorporated therewith;

10 Fig. 2 is a section on the line II—II, Fig. 1, on an enlarged scale;

Fig. 3 is a fragmentary view from the right of Fig. 2;

15 Fig. 4 is a section on the line IV—IV, Fig. 3;

Fig. 5 is a section on the line V—V, Fig. 4; and

Fig. 6 is a section on the line VI—VI, Fig. 2.

20 Furnace 1 is shown as having grate 2 with combustion chamber 3 having stoking opening 4 to be closed by fire door 5 having draft opening 6 therein to be cut off by slide or damper 7. This door is shown as having a

25 heat resisting back 8 with openings 9 there-through to disseminate the air supply as passing through the openings 6 into the combustion chamber 3 for checking the furnace operation. Hereunder the function of these

30 openings 6 through the door are radically changed with increased efficiency in furnace operation. To this end, the openings 6 are left clear of cutting out by slide 7 or the slide 7 may be removed.

35 Insulation sheet 10 may be assembled against the back plate 8 on the combustion chamber side say by water glass to have central opening 11 of this insulation centrally of the door 5. The peripheral series of openings 9 through the back plate 8 are accordingly closed.

40 Bolts 12 having threaded portions 13 may be thrust through the back plate 8 to protrude inward as a ready assembly for engaging

45 slots 14 in flanges 15 of the air pre-warmer device hereunder. This air pre-warmer device is shown as comprising opposing end sections 16 providing return bend portions 17 as seats into which may be thrust free ends 18 of intermediate partition-provid-

ing means herein shown as comprising U-shaped intermediate portion 19 terminating in outwardly extending flanges 20 toward the door back. This U-shaped portion between the upper and lower legs of the U has sinuous 55 partition-providing member 21 therein having anchor means 22 for intermediate portions thereof, with interlock 23 for the terminal toward the door back. There is accordingly provided, at the door back, chamber 24 in 60 communication by perforations 25 with chamber 26 having communication by openings 27 with chamber 28 having communication by openings 29 with chamber 30 which has discharge by perforations or openings 31 into the 65 combustion chamber 3. There is accordingly provided herein in series a plurality of chambers having subdivided communication means due to the perforations when the device is assembled. 70

The assembly occurs by drawing the opposing end sections 16 toward each other with U-bolt 32 and wing nuts 33 thereon coacting against clamp plate or washer 34. This simple assembly of the prewarmer device may 75 be mounted to have slots 14 of the end section flanges 15 supported by the bolts 12 having wing nuts 35 thereon thus mounting the insulation opening 11 to register with the chamber 24 of the prewarmer device. 80

In practice this device is advantageously made of sheet metal of good conducting properties as copper. Furthermore, in the swinging of the door from closed position, the device is of a size not to strike the fire door frame. The location of the prewarmer device as to its inward projection is over the fire or fuel region within the combustion chamber 3. The conductivity of this device, due to the tortuous multi-chamber passage, quickly brings the air temperature upward with resultant air expansion to increase its volume, as much as twice, in many instances of practice. 85

This is an automatically controlled induced draft device for supplying the prewarmed air in the promotion of combustion in the combustion chamber. The perforations 25, 27, 29, 31 gradually increase in total area toward the chamber 3. There is thus provision 90 95 100

to take care of the expansion of the air due to heating with approximation of uniform rate for the automatic draft control according to the forcing rate for the furnace. This is effective as an automatic replenishment of air in quantity for complete combustion even in low grade fuel oil installations as well as in installations using coal and gas. There is economy of as much as twenty per cent to forty per cent in the use of fuel resultant from this readily applied device.

What is claimed and it is desired to secure by Letters Patent is:

1. A combustion promotion device comprising a housing having an intake opening at one end and a delivery opening at the other end, and an additional sinuous sheet metal partition member insertable into the housing and providing with the housing a plurality of chambers in series between said openings.

2. A combustion promotion device comprising a housing having an intake opening at one end and a delivery opening at the other end, and an additional sinuous sheet metal partition member insertable into the housing and providing with the housing a plurality of chambers in series between said openings, there being port means between the different chambers in said series, said port means being in the partition member.

3. A fire door having a perforate back and a draft opening through the door, an annular insulation sheet for closing a peripheral portion of the perforations of the door back, a flanged device against the sheet having a housing extending to a delivery opening remote from the door and an additional sinuous sheet metal partition strip insertable into the housing and providing with the housing a plurality of chambers in series between the openings, and bolts through the device flanges and perforate door back to clamp the insulation sheet in position for anchoring the device to project rearwardly from the door.

In witness whereof I affix my signature.
WILLIAM C. BREWER.
